RAILWAY SWITCH MECHANISM

Reid Abercrombie, Tamms, Ill.

Application May 29, 1943, Serial No. 488,957

6 Claims. (Cl. 246—339)

This invention relates to improvements in mechanism for operating railway switches.

The primary object of the invention is to provide simple and effective means whereby the switch points leading from the main line track to the side track, or siding, may be automatically operated by a device on the engine or train in such manner that the train may be directed onto the siding without bringing the train to a dead stop. A saving of time thus results as well as a substantial saving in fuel which is required to start the engine after it is halted.

Another object is to provide a mechanism of this nature which is operative to automatically, and in response to travel movement of the train in opposite directions, adjust the switch points first to connect the main line and siding and then to clear the main line after the train has either entered the siding, or has left the same ready for travel again upon the main line.

A further object is to provide a switch operating mechanism operative as above which is comparatively simple and convenient of installation, and which is positive and efficient in operation.

With these and other objects in view, the invention resides in the novel construction and arrangement of parts as hereinafter fully set forth and claimed, reference being had to the accompanying drawings, wherein

Figure 1 is a plan view of a railway switch showing the same equipped with the operating mechanism of my invention.

Figure 2 is an upright cross section through one of the remote control, train actuated lever units, being in this case the unit arranged alongside the main line track.

Figure 3 is a similar view showing this unit in process of operation by the train.

Figure 4 is a similar view of the similar lever unit which is disposed alongside the siding track, this view also showing a part of the train.

Figure 5 is an enlarged plan view of the switch box which is disposed adjacent the switch points and which contains the latching mechanism and the lever mechanism for actually swinging the points, this view also showing adjacent parts of the control rods running to the remote control units of Figures 2-4.

Figure 6 is a sectional view along the line 6—6 in Figure 5.

Figure 7 is a horizontal sectional view along the line 7—7 in Figure 6.

Figure 8 is a vertical sectional view along the line 8—8 in Figure 2.

Figure 9 is an end elevation of the switch box

of Figures 5 and 6, showing a part thereof broken away and one of the control rods in cross section.

Referring now with more particularity and by reference characters to the drawings, my invention will be seen to comprise as its main elements a main line remote control unit 10, arranged alongside the main line track A (Figure 1) at a point some distance from the switch, a second remote control unit 11 arranged alongside the track B of the siding, also some distance from the switch, and a switch box, or switching unit 12 disposed laterally of the switch itself. The switch, in accordance with usual practice, comprises swinging switch points C and D which, when swung laterally in one direction connect the siding track with that of the main line so that a train approaching the switch will be guided onto the siding, and when moved in the opposite direction will guide traffic along the main line, the latter usually being the normal position of the points. The usual frog is indicated at E and the ties are generally designated at F. The switch points C and D are connected by a tie bar G to operate in unison.

The main line remote control unit 10 will be first described in detail and for convenience in this description, the direction of travel or movement toward the switch, or leading into the siding, will be termed forward, while the opposite direction will, of course, be termed rearward. The unit 10 comprises a suitable housing 13 which may be secured, as by screws 14, to the ends of ties of extra length provided at the proper point along the main line track A. Arranged in this housing are three levers 15, 16 and 17, which swing about pivots 18, 19 and 20 respectively, mounted in the sides 21 of the housing transversely with respect to the line of travel of a passing train. The upper ends of all three levers project upwardly from the housing through an opening 22 for successive engagement and operation by means of what may be called an operating or actuating member carried by the train. This member is illustrated herein as an arcuate bumper or dog H which is carried by a vertically adjustable arm I in such manner that it may be raised to a position which will clear the levers, or lowered to contact the same as the train passes. Ordinarily, the train will carry at least one of such members H on the engine, on the proper side, and another on the caboose or last car, as shown in more detail and as indicated at J in Figure 4. To properly operate under all circumstances the train will more likely carry such actuating members in pairs, one on each end of the train and on opposite sides

thereof, it being further understood that proper means will be provided (not herein shown) so that they may be raised and lowered conveniently by the trainmen while the train is in motion.

The lever 15 is the first or primary latch release or unlatching lever and at its lower end, below the pin 18, is forked to straddle a latch operating rod 23 which is slidably mounted lengthwise through the housing 13 in openings 24 near its lower end, and which rod extends parallel with the track toward the switch box 12. A stop collar 25 is secured to the rod 23 at one side of the fork 26 on this lever so that movement of the lever in one direction will move the rod endwise while opposite movement of the lever will simply cause the fork to swing clear of the rod without effect on the same. The lever 15 is disposed adjacent the end of the housing 13 remote from the switch so that it will be met first by the actuating member H as the train approaches the switch, and arranged adjacent to the opposite end of the housing is the lever 17 which is adapted also to move the rod 23 in the same direction as lever 15 but in response to swinging movement in a direction opposite to that of lever 15. To this end the lever 17 carries a gear segment 27 which meshes with a similar segment 28 forming a part of a motion reversing or translating lever or crank 29 which swings about a pivot pin 30. The lower end of this lever 29 has a fork 31 straddling the rod 23 and coating with a stop collar 32 thereon, it being readily apparent that swinging movements of lever 17 will be translated into opposite swinging movements of the lever 29, such movement in one direction urging the rod 23 lengthwise, and in the other direction having no effect on the rod as previously described. It will be noted that the respective leverages acting upon the rod 23 by the levers are exactly the same so that the levers 15 and 17 will both move through the same distances in actuating the rod. This lever 17 constitutes the second, or secondary, latch release or unlatching lever.

The lever 16 is disposed between the aforesaid levers 15 and 17 and is fulcrumed upon its pin 19 to move in a vertical plane exactly coinciding with that of the other levers. At its lower end this lever 16, which may be termed the switch control lever, is pivotally connected at 33 to the end of a switch actuating rod 34 extending from the housing, through an opening 35 therein, toward the switch box. This lower end of the lever may of course be offset as represented at 36 to cause the rod 34 to clear the other parts.

The remote control unit 11 is similar to that just described and is mounted alongside the siding track B by means of screws 37 driven into ties suitably extended from the track, as clearly shown, this unit comprising a housing 38 open at its upper end 39 to clear the upper ends of three levers 40, 41 and 42. These levers, exactly corresponding in arrangement and mounting to the aforesaid levers 15, 16 and 17, are mounted to swing about the pivot pins 43, 44 and 45, which are disposed transversely with respect to the line of travel along the siding track. The lever 40 is in this case also provided with a depending lower end forked as at 46 to straddle a latch operating rod 47 similar in function to the rod 23, this lever being hereinafter called the primary latch release lever. The fork 46 cooperates with a stop collar 48 secured on the rod 47 so that swinging movement of the lever in one direction will move the rod lengthwise while opposite movement will allow the fork to swing clear without effect upon the

rod. It will be understood that after each such operation in which the lever swings clear of the rod the return movement will restore the fork to its position straddling the rod ready for further action.

The lever 40 is so disposed in the housing as to be met first by the actuating member H on the train as said train enters the siding, and disposed adjacent the opposite end of the housing 10 38 is the other, or secondary, latch release lever 15 42 which in this case also carries a gear segment 49 for translating its motion. The segment 49 meshes with a similar gear segment 50 carried by the crank 51 which is arranged to swing upon a pin 52. The lower end of the crank 51 has a fork 53 to engage the rod 47 and cooperate with a stop collar 54 thereon in exactly the manner previously described. The rod 47 extends slidably through openings 55 in the ends of housing 20 38 toward the switch box 12.

The lever 41 is disposed intermediate the levers 40 and 42 in the same vertical plane and at its lower end, below the pin 44, is pivotally connected at 56 to a link 57 which extends loosely through an opening 58 in the housing end and exteriorly thereof is pivoted to one end of a rocker arm 59. Said rocker arm is fulcrumed at 60 upon a bracket 61 secured upon the housing and at its lower end, opposite that to which the link is connected, is 25 30 pivotally attached to the end of a switch actuating rod 62 extending therefrom in the direction of the switch box 12. The lever 41, which of course is the switch actuating lever, thus has its motion reversed or translated by the link and rocker arm mechanism for a purpose presently to appear.

Turning now to the switch box 12, the same comprises a housing or box 63 which is secured by screws 64 to the ends of the ties which pass beneath the switch points C and D. The box has a cover 65 hinged at 66 and provided with a lock 67 by which the box is ordinarily kept closed. Within the box there is provided an upright bearing post 68 whereon is fulcrumed a switch lever 69 so that the same may oscillate in a horizontal plane. One end of the lever 69 is pivotally attached at 70 to the end of a connecting rod 71 which extends through an opening 72 in the side of the box toward the switch points C and D and which at its other end is connected thereto as 45 50 55 60 65 represented at 73. The opposite end of the switch lever 69 is pivotally attached to a link 74 extending through another opening 75 in the box and connected exteriorly thereof to a crank 76 fulcrumed at 77 upon a suitable plate 78 secured atop the tie. The other end of the crank 76 is pivotally connected at 79 to one end of the hereinbefore described switching rod 34 and at the same point is pivotally connected to another switching rod 80 which, in effect, forms a continuation of rod 62. For the purpose of connecting the rod 80 to rod 62, and compensating for the offset relation of the two, I provide the assembly of bell cranks and a link designated generally at 81 in Figure 1, these parts being well known in their application.

The switch lever 69 is movable from a normal position shown in full lines in Figure 5 at which the switch points C and D are in their hereinbefore described normal positions, to an angled position shown in broken lines, which position will cause the points to connect the siding with the main line. The switch lever is arranged to be firmly latched or locked in either of such positions by means of a latch plate 82 which is vertically 70 75 adjustable and carried upon a triangular member

83 from which three support pins 84 are depended downwardly and slidably into upright posts 85 formed on the bottom 86 of the switch box. These pins 84 are slideable in the upwardly opening sockets formed in the posts and rest upon expansion coil springs 87 placed therein to bias the latch plate in an upward direction. The latch plate 82 itself is angularly shaped to conform to the included angle between the positions assumed by the opposite sides of the switch lever 69 in its two positions, or in other words, so that one side 88 of the latch plate will engage the edge of the switch lever in its normal position, while the other side 89 will engage an opposite edge of the lever when it is moved to its other adjusted position. Obviously then, the latch plate will prevent movements of the switch lever to and from such positions unless the plate is drawn downwardly beneath the horizontal plane through which the lever swings. When thus lowered the latch plate will be automatically raised again to latching position when released, by action of the springs 87, such movements being carried out and limited by connections now to be described.

Depended from the member 83 is a pivotally suspended link 90 which at its lower end is connected to one end of a bell crank 91 fulcrumed at 92 to a bracket 93 carried by the end of the switch box, and the other end of this crank projects downwardly through an opening 94 in the bottom 86. Beneath the box this lower end of the crank 91 is pivotally attached at 95 to one end of the latch operating rod 47 and is at the same point similarly connected to one end of another rod 96. This rod 96 forms an extension of the latch actuating rod 23 to which it is connected through the medium of a bell crank and link mechanism, designated generally at 97 in Figure 1. This mechanism, of course, compensates for the offset relation of the respective rods 96 and 23 and connects the same to move in unison.

Also connected to the lower end of the link 90 is one end of a hand lever 98 which is fulcrumed upon a bracket 99 in the box and which may be reached by the trainmen to operate the latch plate 82 by hand when the cover 65 is unlocked and opened. Obviously, when the switch box is thus opened the latch plate may be depressed by pulling upwardly upon the handle 100 of the lever 98 after which the switch lever 69 may be moved to throw the switch manually.

It will be noted that the remote control units 10 and 11 each have buffer springs 101 arranged within the ends of the respective housings 13 and 38, and the purpose of these springs is to normally hold the latch actuating levers 15-17 and 40-42 in their normal positions while permitting limited movement of the levers beyond such positions in the direction of the ends of the housings. Such movements of the levers is occasioned by the movement of the train back and forth past these units as will be presently described.

In operation, assuming a train to be approaching the siding and required to enter the same for some purpose, the actuating member H, at the front of the train and on the side at which the remote control unit 10 is located, is lowered by the trainmen and the following operation then takes place without the train coming to a halt. The member H being thus lowered to a level at 70 which it will contact the upper end of the primary latch release lever 15, the movement of the train will swing this lever forwardly or toward the switch causing the forked lower end 26 to urge the latch rod 23 endwise in such manner as 75

to pull upon the lower end of the bell crank 91 in the switch box 12. Such movement of this crank will, as clearly evident, draw the latch plate 82 downward effecting the primary release or unlatching of switch lever 69. Immediately as this takes place, the lever 15 has reached a position such that it contacts the switch actuating lever 16, causing the same to swing in the same direction exerting a pull upon the rod 34 and causing the crank 76 to so move that the link 74 will urge the switch lever to its dotted line position in Figure 5 and set the switch points C and D to a position at which they will guide the train onto the siding. All of such operations take place, of course, before the train actually reaches the switch.

The lengths and relative heights of the upper ends of the levers 15 and 16 are such, with respect to the path traveled by the actuating member H, that as the lever 15 reaches and starts to swing lever 16, it will clear the member H as seen in Figure 3. As this occurs the lever 15 will be freed and may swing back to starting position under influence of the bias exerted by the springs 87 which immediately have a tendency to return the latch plate 82 to locking position. The plate will in fact so return as soon as the switch lever reaches its adjusted position but not before, as should be clear. Prior to its movement, or the initiation thereof, by the lever 15, the lever 16 rests at such an angle that it is below the level of the actuating member H, but it is then moved into the path of the member H and as the train passes, the lever will swing to an equivalent position at the opposite end of the housing 13, again clearing the member, having meanwhile by such movement completed its operation of switch lever 69 as described.

As the train passes the unit 10, the member 40 H will of course impinge the other latch actuating lever 17 swinging it against the resistance of the buffer springs 101 so that it will clear. Such action will not, however, have any effect upon the latch plate since the fork 31 will simply swing clear of rod 23.

Before the head end of the train reaches the other remote control unit, the previously lowered member H may be raised into the clear and the similar member upon the back of the train will be lowered at this time. This member will then engage the primary latch releasing lever 40 in the unit 11, swinging the same in the proper direction to push upon rod 47 and move the crank 91 in the switch box downward to again draw the latch plate 82 downward into the clear. Lever 40 then engaging lever 41 will urge the same toward the opposite end of the housing 38 exerting a pull upon the rod 62 such that the crank 76 will be returned to its initial position, the resulting movement of the switch lever 69 back to normal position again swinging and resetting the switch points C and D to proper positions for traffic along the main line track A. This condition of the remote control unit 11 is that shown in Figure 4.

The lever 40 of course clears the member H, as has been previously described, allowing the latch plate to again secure the switch lever in its normal position.

If the train is then to return to the main line, the same actuating member H will, as it meets the lever 42, and moving in the opposite direction now, swing this secondary latch releasing lever towards and against the lever 41, the first movement being translated through the crank 51

to properly move the rod 47 and draw the latch plate 82 downward to free the switch lever 69. The then ensuing movement of the lever 41 back to its starting position will again swing the switch lever 69 to its dotted line position moving the switch points C and D back to connect the siding and main line tracks. When the train clears the siding the actuating member on the head end of the train will similarly engage the secondary latch actuating lever 17 operating it in the same manner to first unlatch the switch lever 69 and then operating lever 16 to return it to its initial position which, of course, sets the switch points for main line traffic again.

It will be apparent therefore that the train may be switched to and from the siding without coming to a complete stop except as required for standing in the siding, and that all necessary switching operations may be carried out readily by simple control of the various actuating members on the train. A considerable saving of time and fuel will thus naturally result from the use of my invention. Obviously, the parts lend themselves to many applications in connections with various track systems.

I claim:

1. In a railway switch assembly including a switch lever arranged for adjusting the switch points to set positions, of a latch device normally securing the switch lever against adjustments, and at least one control unit arranged alongside the railway remote from the switch for cooperation with an actuating member carried by the train, said control unit including a first lever adapted to be engaged and moved by said member as the train passes and operatively connected to the latch device to temporarily unlatch the switch lever, a second lever in the control unit adapted to be engaged by the first and connected to the switch lever for moving the same to adjust the switch points, the second lever being bidirectional in its movements for adjusting the switch lever in opposite directions in response to travel movement of the train in opposite directions, and a third lever in the control unit and also connected to said latch device and operative by movement of the train in an opposite direction to that affecting the first lever for unlatching the switch lever.

2. In a railway switch mechanism including a switch lever adapted to adjust the switch points to two set positions, of a latch device for normally securing the switch lever against such adjustments, a control unit arranged alongside the railway remote from the switch, a first lever in said control unit adapted for movement in one direction by a train as it passes and connected to the latch device for releasing the switch lever, a second lever in the control unit adapted for operation first by the first lever and then by the passing train, said second lever being connected to the switch lever for adjusting the same in response to such movement and while the switch lever is released from the latch device, the said second lever being also movable in opposite directions by corresponding opposite travel movements alongside to thereby adjust the switch points alternately to their two set positions, and a third lever in the control unit operative by movement of the train in a direction opposite to that affecting the first lever, the said third lever being also connected to the latch device for releasing the switch lever and being adapted to initiate the switch setting movement of the second lever.

3. In a railway switch mechanism including a switch lever adapted to adjust the switch points to two set positions, of a latch device for normally securing the switch lever against such adjustments, a control unit arranged alongside the railway remote from the switch, a first lever in said control unit adapted for movement in one direction by a train as it passes and connected to the latch device for releasing the switch lever, a second lever in the control unit adapted for operation first by the first lever and then by the passing train, said second lever being connected to the switch lever for adjusting the same in response to such movement and while the switch lever is released from the latch device, the said second lever being also movable in opposite directions by corresponding opposite travel movements alongside to thereby adjust the switch points alternately to their two set positions, a third lever in the control unit operative by movement of the train in a direction opposite to that affecting the first lever, the said third lever being also connected to the latch device for releasing the switch lever and being adapted to initiate the switch setting movement of the second lever, the said first and third levers being connected by a common operating rod to the latch device, and means associated with one lever for translating its movements in such manner that the opposite swinging movements of the levers by the train as it passes in opposite directions will move the operating rod in exactly the same manner.

4. In a railway switch mechanism of the kind described, for operating the switch of a switch track leading from a main track, said switch including conventionally hinged switch points connected to and operable by a switch connecting rod for movement alternately to direct a train either over the main track or over the switch track, a switch box transversely aligned with the switch points and into which box the switch connecting rod is slidably extended, a switch operating lever mounted within the box through a medial point of the lever to oscillate in a horizontal plane, one end of this lever being connected to the free end of the switch connecting rod within the box for moving the latter to close or open the switch, a vertically movable switch latch mounted in the box at the opposite latch end of the switch operating lever and spring biased to normally rise to either side of the lever as the latter is oscillated for releasably latching the same to either of its alternate positions for holding the switch closed or open, latch release rods slidably mounted underneath the switch box and latch in parallelism with the tracks, connections within the switch box between the latch release rod thereunder and the said spring biased latch for pulling the latch downward on the movement of the latch release rod, thereby clearing the switch operating lever and permitting the same to swing thereover, the said latch release rod being normally held to its retracted position within the box through its connection with the said spring biased latch.

5. In a railway switch mechanism according to claim 4, separate means suitably spaced alongside the main and switch tracks at each side of the switch box and connected at each side with the extended ends of the latch release rod of the box for thrusting said rod contrary to the action of the spring biased latch and for thereby releasing said latch, said means being

actuatable by bumpers upon the ends of a train moving onto or off of the switch track, and means also operable by said bumpers and connected with the latch end of the switch operating lever for swinging this lever and the switch connecting rod and switch points over the said latch to their other and alternate positions for closing or opening the switch as the train either prepares to enter the switch track or to leave the same.

6. In a railway switch mechanism according to claim 4, a pair of latch release units spaced alongside the main and switch tracks at each side of the switch box and connected with the extended ends of the latch release rod thereof for slidably urging said rod contrary to its nor-

mal retracted position, for releasing the latch and freeing the switch operating lever, switch operating units cooperatively associated with the latch release units for operating the switch mechanism immediately after the release of the latch, the latch release units and the switch operating units being both actuatable by bumpers upon the ends of a train moving in either direction over the tracks, said switch operating units including means for resetting the switch to open the main line after each switch closing operation of the mechanism for the passing of a train over the switch track in either direction.

REID ABERCROMBIE.
